UNITED STATES PATENT OFFICE

SOPHUS RASMUSSEN, OF ALBERT LEA, MINNESOTA

CARBURETING APPARATUS FOR LIGHTERS

Application filed June 7, 1928. Serial No. 283,640.

This invention relates to a stove adapted to use liquid hydrocarbon fuel, and particularly to a lighting device for such a stove. Such stoves are now used in large numbers and it has heretofore been necessary to start 5 said stoves by heating a vaporizing member comprised therein by means of a priming charge of fuel, or by means of a separate torch. This lighting operation has been a necessary preliminary operation to light the 10 main burners of the stove and has been one of the objections to such stoves. It is desirable to have a stove structure which can be lighted at once by an ordinary match without the use of a torch or other separate means 15 by a priming device of the vaporizing member.

It is an object of this invention, therefore, to provide a simple and efficient structure of 20 a stove using a vaporizing fuel, by means of which the stove can be lighted with an ordinary match without any preliminary heating of the vaporizing member by priming or by a separate means, such as a torch.

It is a further object of the invention to 25 provide a structure of stove using liquid vaporizing fuel having a burner and a vaporizing member for said burner, together with means for furnishing a combustible mixture 30 to said burner for heating said vaporizing member, whereby said burner can be instantly lighted with an ordinary match or other lighting device.

It is a further object of the invention to 35 provide a structure of stove using liquid vaporizing fuel comprising one or more main burners, a vaporizing member therefor, a fuel tank adapted to contain the fuel under pressure to which said vaporizing member is connected, and means connected to said fuel tank 40 adapted to receive and discharge a combustible mixture which can be instantly lighted to heat said vaporizing member.

It is more specifically an object of the invention to provide a structure of stove using liquid vaporizing fuel and having one or more main burners, a vaporizing member for said burners connected to a fuel tank adapted 45 to contain a fuel under pressure, a starting 50 burner of the retort type for heating said

vaporizing member, and means connected to said starting burner and fuel tank, adapted to supply a charge of a combustible mixture which can be instantly lighted to start said auxiliary burner.

These and other objects and advantages of the invention will be fully set forth in the following description made in connection with the accompanying drawings, in which like reference characters refer to similar parts throughout the several views and in which:

Fig. 1 is a partial plan view of the stove having the invention applied thereto, as indicated by the arrows;

Fig. 2 is a vertical section taken on line 2-2 of Fig. 1 as indicated by the arrows;

Fig. 3 is a vertical section taken on line 3-3 of Fig. 1 as indicated by the arrows;

Fig. 4 is a view similar to Fig. 3 showing 70 a modification; and

Fig. 5 is a vertical section taken on line 5-5 of Fig. 4, Figs. 4 and 5 being shown on an enlarged scale.

Referring to the drawings, a stove is shown 75 having a frame comprising the top plate 10 and the supporting frame 11 to which said top is secured. A fuel tank 12 is shown, disposed at one end of the frame 11 and secured thereto by straps 13 extending around the 80 tank and secured to said frame. One of the main burners of the stove is shown as 14, connected to a mixing chamber 15 a portion of which is shown and which is secured to the top plate 10 by the screws 16. A vaporizing 85 member or tube 17 connects with mixing chamber 15 at one end and projects through a frame 11 at one end, the same being connected to the tank 12 by a small tube or conduit 18 which is connected to a fixture 19 secured in 90 tank 12. Vaporizing tube 17 is controlled so as to be opened or closed and supply or shut-off fuel to mixing chamber 15 respectively, by a valve having an operating hand wheel 17a. Said fixture comprises a gauge 20 adapted to 95 show the pressure that the fuel is under in tank 12 and is also provided with a valve operated by hand wheel 21.

An auxiliary burner for heating the vaporizing tube 17 is provided, and while this 100

burner may be disposed in various places, it is shown as disposed between mixing chamber 15 and burner 14 and indicated generally at 5 22. This burner comprises a mixing chamber 22a illustrated as a curved conduit having an open upper end into which projects a small vaporizing tube 22b connected to a valve body 24 having therein a valve 25 for opening and closing tube 22b, which valve is operated by 10 the hand wheel 26. The valve body 24 has a flange thereon connected to the frame 11 by headed and nutted bolts 27 and has a depending lug in which is secured and from which projects a rod 28 forming a support 15 for mixing chamber 22a. The member 22a has a lower opening 22c disposed below vaporizing tube 22b and vaporizing tube 17, from which the flame of said burner projects. The conduit connecting mixing chamber 20 15 and burner 14 has a pan 23 therein, adapted to catch any overflow from burner 22 and return the same to the mixing chamber 15.

A small tube or conduit 29 connects valve body 24 to a valve body or fixture 30 secured 25 to the bottom of tank 12 by being threaded into a plug 31 secured to and extending into said tank. Valve body 30 has a passage 30a extending therethrough, controlled by a valve stem member 31a which is in turn operated 30 by the hand wheel 32. The stem 31a is packed by a cap 33 threaded onto body 30, adapted to compress packing 34 against the end of said body and about said stem. It will be noted that stem 31a has a valve portion 35 31b engaging a portion of passage 30a as the valve seat. A small tube 35 is threaded into the top of body 30 and in the portion extending through plug 31, which tube 35 has an open upper end which is disposed in 40 the air space in tank 12 as indicated in Fig. 3. The tube 35 has a small aperture 35a adjacent its bottom and adjacent member 30 which is disposed in the gasoline or fuel in tank 12 and affords communication of tube 35 with 45 said fuel. Aperture 35a is surrounded by a fine screen 36 shown as cylindrical in form, surrounding a portion of valve body 30 at its lower end and a cylindrical portion 37a of an upstanding member 37 at its upper end, which member 37 fits tube 35 and is secured to 50 body 30.

In the operation of the structure described, when the stove is not in use, all of the valves described are closed. The fuel is thus shut-off from both the burner 22 and burner 14 and vaporizing tube 17. When the stove is to be lighted, valve wheel 32 will be turned, thus opening passage 30a and valve wheel 26 will be turned to open communication with 55 the burner 22 and small vaporizing tube 22b. A small amount of fuel passes into tube 35 through opening 35a and when the said valves are open, the pressure of air in tank 12 forces this fuel through passage 30a through tube 60 29 to valve body 24, and through tube 22b.

This passage of this air and fuel forms a combustible mixture, which mixture is discharged at the end of tube 22b passing into mixing chamber 22a, and the same can be at once lighted at the opening 22c. It is not necessary to preliminarily heat the vaporizing tube 22b, but the burner can be lighted as soon as the valve controlling the same is opened. This initial charge of combustible mixture furnishes sufficient flame to heat the vaporizing tube 22b and as fuel continues to flow through this tube from tank 12 through conduit 29, the burner will continue in operation, thus heating vaporizing tube 17. The burner 22 is only burned for a very short period, after which valve wheel 17a is operated to permit fuel to pass through vaporizing tube 17 to the mixing chamber 15. This fuel is vaporized, mixed with air in chamber 15, and is delivered to burner 14 which can now be lighted. After the main burner 14 is lighted, valve wheels 26 and 32 are again turned to close valves 25 and 31. The stove now continues in operation until it is desired to shut off the main burners, which is done by closing the vaporizing tube 17 by turning hand wheel 17a. It is thus seen that no vaporizing member has to be heated by holding a torch thereunder, or holding a match thereunder, and it is not necessary to use a small separate supply of gasoline to be ignited under the vaporizing tube to heat the same. The burner 22 can be instantly lighted and continued in operation for a very short period, after which the main burners can be lighted.

In the modification shown in Fig. 4, the structure is the same as described, except that conduit 29 is connected to a valve body or fixture 38. This body has a passage 38a therethrough closed by a valve portion 39a on a valve stem 39 threaded in valve body 38 and operated by valve wheel 40. The valve stem 39 is packed by a cap or shell 41 threaded thereon and which compresses packing 42 against the end of body 38 and about valve stem 39. The valve body 38 is secured to the bottom of the tank 12 by being threaded into a plug 44 fitted in said tank and extending thereto. A tube 43 is secured in the top of body 38 and has an open upper end disposed in the air space in tank 12. A passage 38b extends downward in member 38 and communicates with passage 38a. Said passage 38b communicates with passage 38a through the small opening 38c and valve stem 39 has a reduced portion 39b extending from the valve portion 39a and having a conical end adapted to project into opening 38c. A plug 46 is threaded into the top of member 38, having a passage therethrough communicating with the passage 38b, which plug has a reduced portion at its upper end surrounded by a screen cap 45 which is of cylindrical form and fits on plug 44.

In the operation of the device shown in Figs. 4 and 5, when the stove is to be started, valve 39a will be opened by turning hand wheel 40. The valve 25 will also be opened 5 by turning valve wheel 26. Gasoline will pass into passage 38b through the screen 45 and to the valve 39a. When this valve is opened, this gasoline will be forced out through passage 38a by the pressure of air in 10 tube 43 and this air passing through the tube with said gasoline or fuel will form a combustible mixture which will be discharged into the burner 22. This burner therefore can be lighted at once with an ordinary 15 match. After the combustible mixture is consumed, the gasoline or fuel continues to flow from tank 12 through passage 38b so that burner 22 continues in operation. This burner, as stated above, burns only for a 20 short period so as to heat vaporizing tube 17, after which hand wheel 17a is turned to admit fuel through the vaporizing tube 17 to the main burners. The main burners are now lighted and valves 25 and 39a then closed. 25 The main burners are now continued in operation as long as desired and will be extinguished when no longer needed, by turning valve wheel 17a. The screens 36 and 45 prevent any solid or foreign matter entering the 30 small passages 38a or 38b respectively. The portion 38c with its pointed end keeps the opening between passage 38b and 38a open.

From the above description it is seen that applicant has provided quite a simple and efficient structure by means of which the stove can be instantly lighted without the preliminary heating of any vaporizing member. The objectionable operation of priming the stove or preliminarily heating the same by a 40 torch is eliminated. The improved structure is quite simple, involving few parts, and the same are easily manipulated. The device has been amply demonstrated in actual practice and found to be very successful and efficient. 45

It will, of course, be understood that various changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claim. 50

What is claimed is:—

A lighting device for a liquid hydrocarbon stove having a fuel tank adapted to contain fuel under pressure, one or more main burners, a vaporizing member, and means connecting said tank to said vaporizing member, an auxiliary starting burner adapted to heat said vaporizing member, a valve body secured in the bottom of said tank having a passage extending therethrough, a valve for opening 60 and closing said passage, a tube connected to 65

said valve body and passage and projecting upwardly in said fuel tank, having an open upper end disposed in the air space in said tank, said tube having a small aperture therein in adjacent said valve body, a tube connecting said valve body and passage to said auxiliary burner, and a valve for controlling said auxiliary burner. 70

In testimony whereof I affix my signature.

SOPHUS RASMUSSEN.
